UNITED STATES PATENT OFFICE.

MILTON M. MIKAN, OF DURAND, MICHIGAN.

CATTLE-STANCHION.

1,184,197.

Specification of Letters Patent. Patented May 23, 1916.

Application filed November 6, 1914. Serial No. 870,673.

To all whom it may concern:

Be it known that I, MILTON M. MIKAN, a citizen of the United States, residing at Durand, in the county of Shiawassee and State of Michigan, have invented new and useful Improvements in Cattle-Stanchions, of which the following is a specification.

This invention relates to improvements in cattle stanchions and means for locking and releasing the same the invention consisting in the construction, combination and arrangement of devices hereinafter described and claimed.

One object of my invention is to provide improved means for simultaneously locking or releasing either one of a number of stanchions, and thereby avoid the necessity of going into the separate cattle stalls for locking or unlocking the stanchions thereof.

Another object is to provide means for disconnecting the stanchion locking and unlocking devices from the common actuating rod to enable any desired stanchion or stanchions to remain inoperative when the others are locked or released.

In the accompanying drawings: Figure 1 is a side elevation of a cattle stanchion and locking and releasing means therefor constructed in accordance with my invention and showing the stanchions in locked positions. Fig. 2 is a detail elevation on a larger scale of one of the stanchions and its locking and releasing means, showing the stanchion in open position. Fig. 3 is a detail horizontal sectional view on a plane indicated by the line *a—a* of Fig. 1. Figs. 4 and 5 are detail views. Fig. 6 is a detail perspective view of the catch for locking the bars in closed position. Fig. 7 is a detail perspective of the mechanism for preventing movement of the rod.

My improved cattle stanchion locking and releasing mechanism is adapted for operation in connection with one or any desired number of stanchions. Each stanchion 1 is provided with vertically arranged pivots 2—3 at its upper and lower ends which are mounted in pivot bearings in a plate or other elevated device 4 and in a sill or other base support 5. The lower pivot 3 is provided with a stop 6 which may be of any suitable construction and which coacts with a fixed stop 7 to limit the movement of the stanchion so that the latter can only turn through about one fourth of a circle. On one side of the stanchion is a movable bar 8

which is hinged or pivotally mounted at its lower end as at 9 and is adapted, at its upper end, to close against the head 10 of the stanchion as at 11. The stanchion head has a shoulder 12 and the bar 8 carries a pivotally mounted catch 13 which is adapted to engage the shoulder 12 to lock the bar 8 in closed position. Said bar is also provided with a spring 14 to snap the catch 13 into engagement with the shoulder 14 when the bar closes. The said catch is provided at its engaging end with a semi-circular arm 15 for a purpose presently described.

A common operating rod 16 for the releasing and locking devices of all the stanchions is mounted for longitudinal movement on standards 17 which are here shown as arranged on the plate 4, these stanchions being preferably provided with rollers 18 which bear against said operating rod and lessen friction. A spring 19 is connected to one end of the rod 16 to move the latter in one direction. A chain 20 is attached to the opposite end of the rod and is engaged with a wheel 21 which is mounted on an axle 22 the bearings of which are secured at one side of the barn or stable in which the stanchions are located. On one side of the wheel 21 is a clutch 23.

A sprocket wheel 24 is mounted on the axle shaft 22 for rotation thereon and has a clutch element 25 on one side which may be engaged with or disconnected from the clutch element 23 to lock said wheel 22 to the wheel 21 or release it therefrom. A shifting lever 26 is provided to thus lock or release the wheel 24. An operating chain 27 is engaged with the wheel 24 and is adapted to be manually operated to coact with said wheel to cause the wheel 21 to be turned therewith when the wheel 24 is in clutched position. When the wheel 24 is clutched to the wheel 21 and is turned in one direction by the chain 27 the operating rod 16 is caused to move longitudinally in one direction against the tension of the spring 19, to close the stanchions. Each stanchion bar 8 is provided near its upper end with a horizontally arranged semi-circular arm 28, the central portion of which is attached to the bar 8 and said semi-circular arm or curved arm is provided with a curved slot 29 which extends nearly from end to end thereof. In

connection with each curved arm 28 I provide an operating lever 30 which is here shown as fulcrumed as at 31 and the upper

end of which is loosely connected to the operating lever 16 by being passed through a slot 32 in said rod. To the lower end of each operating lever 30 is pivoted a link arm 33 as at 34, said link arm having a depending stud 35 which is dropped into the slot 29 and hence is detachably connected to the curved arm 28 and is slidably connected to said curved arm so that the latter may 10 turn with the stanchion and enables the stanchions to permit free movement of the animal held thereby. Counteracting springs 36 are connected to the ends of the arm 28 and to opposite sides of the link arm 33. Said springs yield to the swinging movement of the stanchion occasioned by the movements of the animal but tend to keep the stanchion parallel or approximately so with the operating rod 16 to facilitate the 20 movement and operation of the levers 30. In connection with each stanchion I also provide a catch releasing lever 37 which is fulcrumed at 38 and the lower end of which is arranged above the stanchion and 25 at one side of the curved arm 15 of the catch. The upper end of said lever is near the rods 16 and in the path of a block 39 which is longitudinally movable on said rod 16 being provided with a tubular portion 40 through which said rod extends said tubular portion having a bayonet slot 41 in one side and the rod being provided with a pin 42 which projects from one side thereof and is adapted to engage said slot. When 35 the pin is engaged with the inner end of the slot the block is locked to the rod 16 for movement therewith.

In the operation of my stanchion releasing and locking devices, when the rod 16 is 40 moved by the chain 20 and coacting devices in one direction against the tension of the spring 19 the levers 30 are turned in the required direction to cause the link arms 33 to coact with the curved slotted arms 28 to 45 close the stanchions by moving their bars 8 inwardly, the catches 13 engaging the shoulders 12 and locking said bars in closed position, as will be understood. When the wheel 24 is unclutched from the wheel 21 50 the spring 19 acts to move the rod 16 in the reverse direction, thereby causing the levers 37 to be engaged by the blocks 39 and turned so that said levers engage the curved arms 75 of the catches and release the catches 55 from the shoulders 12, the levers 30 being also turned by said rod 16 and their link arms 33 coacting with the curved slotted arms 38 to open the bars 8 as will be understood. Within the scope of my invention 60 any suitable means may be employed for operating the rod 16 and operating means therefor may if desired be installed on opposite sides of the barn or stable. At one side of each stall I also provide a receiving 65 fork 43 to engage and hold the bar 8 when

the latter is opened. When it is desired that any one of the stanchions remain closed with the others when they are opened the block 40 of said stanchion may be adjusted lengthwise on the rod 16 so as to disengage 70 its slot 41 from the pin 42 and thereby clear the lever 37 and the link arm 33 of the lever 30 may be lifted and its stud 35 disengaged from the slot 29, as will be understood. 75

Having thus described my invention, I claim:—

1. In combination with a pivotally mounted stanchion having a movable bar on one side, means to lock said bar in closed position, a curved slotted arm on said bar, a lever, a link pivotally connected to the lever and having a stud to engage the slot of said curved arm and means to operate said lever. 80
2. In combination with a pivotally mounted stanchion having a movable bar and means to lock said bar in closed position, a curved arm on the bar locking means, a releasing lever arranged to engage said curved arm and thereby trip the releasing means, and means to operate said releasing lever. 90
3. In combination with a stanchion having a movable bar and means to lock said bar in closed position, an operating lever connected to said bar to open the same, a releasing lever to trip the bar locking means, a longitudinally movable operating rod to which the first named lever is connected and a block on said rod to engage and operate the releasing lever when said rod is moved in the required direction to cause the operating lever to open the stanchion. 95
4. In combination with a stanchion having a movable bar and means to lock said bar in closed position, an operating lever connected to said bar to open the same, a releasing lever to trip the bar locking means, a longitudinally movable operating rod to which the first named lever is connected and a block on said rod to engage and operate the releasing lever when said rod is moved in the required direction to cause the operating lever to open the stanchion, a spring 105 to move said rod in one direction and manually operated means to move said rod in the reverse direction. 110
5. In combination with a stanchion having a movable bar and means to lock said bar in closed position, a releasing lever connected to said bar to open the same, a releasing lever to trip the bar locking means, a longitudinally movable operating rod to which the first named lever is connected 115 and a block on said rod to engage and operate the releasing lever when said rod is moved in the required direction to cause the operating lever to open the stanchion, a spring 120 to move said rod in one direction and manually operated means to move said rod in the reverse direction. 125
6. In combination with a stanchion having a movable bar and means to lock said bar in closed position, a releasing lever connected to said bar to open the same, a releasing lever to trip the bar locking means, a longitudinally movable operating rod to which the first named lever is connected 130 and a block on said rod to engage and operate the releasing lever when said rod is moved in the required direction to cause the operating lever to open the stanchion, a spring 135 to move said rod in one direction and 140

manually operated means to move said rod in the reverse direction said manually operating means comprising a wheel and axle, the former connected by a chain to the rod, 5 an operating wheel, and a clutch to engage said operating wheel with the first named wheel.

In testimony whereof I affix my signature in presence of two witnesses.
